UNITED STATES PATENT OFFICE.

JAMES D. HALLORAN, OF NEW YORK, N. Y.

AIR-SUPPLY DEVICE FOR FIREMEN.

1,040,311.

Specification of Letters Patent.

Patented Oct. 8, 1912.

Application filed June 7, 1911. Serial No. 631,732.

To all whom it may concern:

Be it known that I, JAMES D. HALLORAN, a citizen of the United States, and a resident of the city of New York, Elmhurst, borough of Queens, in the county of Queens and State of New York, have invented a new and Improved Air-Supply Device for Firemen, of which the following is a full, clear, and exact description.

10 The object of the invention is to provide a new and improved air supply device for firemen, arranged to utilize the action of the water passing through the fire hose for drawing in fresh air and delivering the same to one or a number of firemen for breathing purposes, thus enabling the firemen in charge of the fire to readily and successfully combat a fire in the holds of vessels, cellars and other places.

20 For the purpose mentioned, use is made of an air suction device connected with the fire hose and adapted to draw in fresh air by the suction action of the water passing through the fire hose, and distributing means connected with the said suction device for distributing the drawn in air to the firemen for breathing purposes.

25 A practical embodiment of the invention is represented in the accompanying drawings forming a part of this specification, in which similar characters of reference indicate corresponding parts in all the views.

30 Figure 1 is a perspective view of the air supply device in use; Fig. 2 is an enlarged side elevation of the air supply device, parts being in section; Fig. 3 is an enlarged sectional side elevation of the breathing hood as applied and Fig. 4 is an enlarged sectional side elevation of part of the air supply de-
vice.

40 The fire hose A is provided with the usual regulation nozzle B, on which is removably secured a nipple C forming with the nozzle B an air suction chamber C' connected with a pipe D of sufficient length to reach to the outside of the building, the outer end of the pipe being provided with a perforated bulb E, to keep the air passing into the pipe D as free from dust as possible. It is understood that when the fire hose A is in use and the water passes through the nozzle B, then a suction is produced in the nipple C and its chamber C', whereby fresh air is drawn in through the pipe D from the outside. The pipe D is preferably provided with a flexible section D' and a rigid section

D², coupled or otherwise connected with a section D³, preferably forming part of the nipple C.

Within the rigid section D² of the pipe D are arranged a plurality of funnels F, extending rearwardly, so that air passing through the pipe D can readily pass into the funnels F. The funnels F extend to the outside of the pipe section D², and the outer ends of the funnels are coupled or otherwise connected with flexible pipes G, each coupled or otherwise connected at its end with a breathing hood H of hard rubber, metal, or other suitable material. The breathing hood H is provided with an opening H' for the passage of the nose of the fireman, and the said hood is also provided with a lip H² adapted to pass into the fireman's mouth so as to support the breathing hood H on the face of the fireman, thus leaving the latter's hands and arms free for manipulating the hose A and its nozzle B to direct the water to the fire. The breathing hood H is also provided with perforations H³ for the exhalations of the fireman, and the opening H' of the hood is preferably lined with rubber or other soft material H⁴, to fit snugly on the fireman's face and thus prevent smoke from passing into the hood H.

When fighting a fire in the hold of a vessel or in a subcellar of a building or the like, usually an officer and several firemen have charge of the hose A, and, by the arrangement described, the officer and each fireman is provided with a breathing hood H connected by the pipes G with the funnels F, so that each is supplied with air drawn through the pipe D by the suction action of the water passing through the nozzle B at the nipple C.

45 From the foregoing it will be seen that a number of firemen are supplied with fresh air while in dangerous places, and hence can readily combat with the fire without danger of being smothered by the smoke arising from the fire.

50 Check valves O are preferably arranged in the couplings I connecting the funnels F with the pipes G, (see Fig. 4) so that a suction is prevented in the funnels F, pipes G and hood H, while the fresh air coming in through the pipe D can readily pass into and through the funnels F and pipes G to the hood H and to the fireman.

55 While I have shown and described my air supply device as being used in connection

- with a fire hose delivering water, I wish to have it understood that I may also use it with a tube or conduit adapted to deliver fluids in general when the same are to be utilized for the purpose of extinguishing fires, so long as the action of the fluids passing through the hose or conduit suffices to draw in air through the air supply pipe connected thereto.
- 10 Having thus described my invention, I claim as new and desire to secure by Letters Patent:
1. In an air supply device, the combination with fire hose having a nozzle, an air suction device exteriorly connected with the said nozzle at the discharge end thereof for drawing in air by the passage of the water through the nozzle, a main air supply pipe connected with the said suction device for drawing in air through the air supply pipe independent of the said fire hose, tapping means connected with the said main air supply pipe for tapping the latter for air, and distributing means connected with the said tapping means for distributing the tapped air to the firemen for breathing purposes.
  2. In an air supply device, the combination of a fire hose having a nozzle, a suction nipple at the said nozzle and forming a suction chamber with the same, a main air supply pipe connected with the said suction chamber, funnels in the said main air supply pipe, branch air supply pipes connected with the said funnels, and breathing hoods connected with the said branch air supply pipes and adapted to be carried by the firemen to supply the latter with fresh air.
  3. An air supply device for a fire hose, having a nozzle, comprising a suction nipple for attachment to the nozzle to form a suction chamber, a main air supply pipe connected with the said nipple and having a rigid and a flexible section, funnels extending rearwardly within the rigid section of the air supply pipe, a branch air pipe connected with each funnel, and a breathing hood on the end of each branch air pipe.
  4. In combination with a fire hose having a nozzle, a suction nipple for attachment to the discharge end of the said nozzle to form a suction chamber, a main air supply pipe connected with the said nipple and having a rigid and a flexible section, funnels extending rearwardly within the rigid section of the air supply pipe, a branch air pipe connected with each funnel, and a breathing hood on the end of each branch air pipe, the said hood having means for supporting the hood on the fireman's face and having means for the escape of vitiated air.
  5. In an air supply device, the combination with a fire hose having a nozzle, an air suction device exteriorly on the said nozzle for drawing in air by the passage of the water through the nozzle, a main air supply pipe connected with the said suction device and independent of the fire hose, a funnel extending within the said main air supply pipe for receiving a portion of the air drawn in, and distributing means connected with the said funnel to make a portion of the air drawn in through the said suction device available for breathing purposes.
  6. In an air supply device, the combination with a fire hose having a nozzle, an air suction device exteriorly connected with the said nozzle and surrounding the terminal thereof for drawing in air by the passage of the water through the nozzle, a main air supply pipe connected with the said suction device and independent of the said fire hose, a plurality of funnels within the said main air supply pipe, a plurality of air-distributing pipes connected with the said funnels, and breathing hoods on the ends of the said distributing pipes.
  7. In an air supply device, the combination with a fire hose having a nozzle, an air suction device detachably connected with the said nozzle and surrounding the same at the forward end for drawing in air by the passage of the water through the said nozzle, a main air supply pipe having a flexible section and a rigid section connected with the said suction device, a plurality of funnels within the said rigid section of the main air supply pipe connected with the said funnels, and breathing hoods on the terminals of the said distributing pipes.
  8. In an air supply device, the combination with a fire hose having a nozzle, an air suction device detachably connected with the said nozzle and surrounding the same at the forward end for drawing in air by the passage of the water through the said nozzle, a main air supply pipe having a flexible section and a rigid section connected with the said suction device, a plurality of air distributing pipes, funnels at one end of the air distributing pipes and arranged within the said rigid section of the main air supply pipe, the mouths of the funnels being toward the incoming air, and breathing hoods at the other ends of the said distributing pipes.
- In testimony whereof I have signed my name to this specification in the presence of two subscribing witnesses.
- JAMES D. HALLORAN.
